UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

SPOOL VALVE FOR ROCK DRILLS.

Application filed March 29, 1922. Serial No. 547,872.

To all whom it may concern:

Be it known that I, LEWIS C. BAYLES, a citizen of the United States, and a resident of Easton, county of Northampton, and State of Pennsylvania, have invented a certain Spool Valve for Rock Drills, of which the following is a specification accompanied by drawings.

This invention relates to fluid actuated hammer drills but more particularly to a motive fluid distributing valve of the spool type, such as disclosed in my co-pending application, Serial No. 451,661, filed March 12, 1921, for controlling both the inlet and exhaust from both ends of the cylinder of the machine.

Valves of this type, especially for a large machine, are ordinarily of substantial size and weight, and impact with considerable force against the valve stops which limit their movement, which may injure the valve faces, in case the impact takes place on such faces, or cause breakage.

The objects of the present invention are to produce a valve of the type described, which is light and strong and is at the same time provided with stops which limit the valve movement without permitting the edges of the end faces of the valve to abut against adjacent parts of the valve structure, so that control of the motive fluid at the end faces is effected solely by sliding contact between the valve and the part or parts within which it is contained.

Further objects of the invention are to enable the impact of the valve to be cushioned in a valve structure which may be readily assembled, but securely held in alignment in the valve chest by simple means capable of withstanding severe usage.

The invention is shown in one of its preferred forms in the accompanying drawings, in which

Figure 1 is a top plan view, partly broken away and partly in horizontal section through the valve chest, of so much of a rock drill as will serve to illustrate the invention.

Figure 2 is a diagrammatic longitudinal sectional elevation through the valve chest and a portion of the cylinder, with the chest and cylinder conventionally shown in the same plane for clearness of illustration, and

Figure 3 is a detail perspective view of a form of cushioning device.

Referring to the drawings, a fluid actuated rock drill of the hammer type is shown, having the cylinder A, the front head B and the back head C, adapted to be held together by the usual side bolts D. The drill steel E extending into the front head, is adapted to receive the impact blows of the hammer piston F (see Figure 2) reciprocating in the cylinder A and provided with the reduced shank or extension G, guided in the front cylinder washer H.

The supply and distribution of motive fluid for operating the tool is controlled by the usual throttle valve J and the spool valve K, mounted in the valve chest L, which is adapted to be secured on the side of the cylinder, as by means of the bolts O. The throttle valve J controls the inlet P and is provided with the operating handle Q which is limited in its rotary movement by a stop R. Motive fluid enters at the inlet P, passes through the throttle valve J to the supply passage S in the valve chest which branches and leads to the inlet ports T controlled by the distributing valve K.

The construction and operation of the spool valve K and the distribution of motive fluid in the machine can more readily be described and followed by reference to the conventional diagrammatic view shown in Figure 2 in which the valve is shown longitudinally of the cylinder A and the various ports and passages are assumed, for simplicity, to all be in one longitudinal plane, the relative positions of the ports however, remaining the same as in the actual construction indicated in Figure 1. Figure 2 shows the piston F at the rearward end of its stroke and about to start forwardly.

In the construction of the valve K and its associated parts, which form the principal subject matter of the present invention, the cylinder A and valve chest L are formed with suitable ports and passages, for distributing motive fluid to both ends of the cylinder and for exhausting the fluid from the cylinder. The spool valve K is of special construction and is formed with hollow or recessed end faces *a* and *b* which are utilized to control the inlet to both ends of the cylinder, while an enlarged central flange *c* controls the exhaust from both ends of the cylinder, and a central bore or opening *d* at the center of the valve permits a bolt *e* to be placed through the valve for

holding the parts of the valve structure together and within the valve chest.

The valve operates in the flanged bushings X and Y which are adapted to be inserted 5 from opposite ends into the bore of the valve chest. These bushings as shown, are spaced apart or separated at their inner opposed faces, leaving a space Z forming an exhaust passage through the chest communicating 10 with the exhaust port f and after the bushings and valve have been assembled in the valve chest, the bolt e is tightened to hold the parts in place, and form a guide for the valve.

15 By making the ends of the valve K hollow, the valve is made as light as practically possible, and this also affords means for providing valve stops, preferably in the form of sleeves g and h within the valve bushings, 20 against which stops the bottom portions j and k of the recessed end faces of the valve are adapted to abut for limiting the movement of the valve, without permitting the edges o and p of the end faces to abut 25 against adjacent parts of the bushings or stops. By this means, control of the motive fluid at the end faces of the valve is effected solely by sliding contact between the valve and the bushings, because the edges o and 30 p of the valve are permitted to over-run the inlet ports which they control. The impact of the valve against the stops takes place between the solid central portion of the valve and the ends of the stops, and 35 the thinner and lighter edges o and p of the end faces are protected from impact.

In order to further insure the valve 40 against breakage, suitable cushioning means are provided for the stops g and h of any suitable type or form, and in this instance, 45 metallic cushioning devices in the form of bent washers q and r are provided between the stops g and h and the cover plates t and u placed over the ends of the valve bushings X and Y respectively. A detail view 50 of one of these bent spring washers is shown in Figure 3, but any other suitable form of buffers could be used. The actual deformation of the buffers is slight and they are for the purpose of softening the blow of impact 55 of the valve against the stops.

The valve chest L and valve bushings, in addition to the functions supplied by the inlet ports T and the exhaust port f located 60 between them at one side of the chest, affords communication with admission ports v and w leading to points near the forward and rearward ends of the cylinder, and also affords communication with exhaust ports x and y opening into the cylinder at points between the admission ports v and w and the center of the cylinder. For these purposes, 65 the valve bushings X and Y are provided with supply passages connecting the valve chest inlet ports T and the cylinder admis-

sion ports v and w, and the recessed end faces a and b of the valve K control the said supply passages through the valve bushings and by this means control the inlet to both ends of the cylinder through the admission 70 ports, while the enlarged central flange c of the valve controls the exhaust passage or space Z between the opposed faces of the bushings and thus controls the exhaust from both ends of the cylinder through the exhaust ports.

The opening d through the center of the valve K is made slightly larger in diameter than the diameter of the bolt e so as to prevent binding, the flow of air through this space being cut off by the stops when the valve is in either extreme position. The period in which the valve is in intermediate position is so short that the leakage through this space will not affect the action.

80 In the operation of the machine, let it be assumed that the piston F is in the position indicated in Figure 2 at the rearward end of its stroke, and it is starting forwardly. The valve K has moved over to the position 85 indicated in said figure and motive fluid is being admitted from the inlet port T through the admission port w to the rearward end of the cylinder as indicated by the arrows. The exhaust from the forward 90 end of the cylinder is open through the exhaust passage x and the exhaust port f to atmosphere. As the piston in its forward travel uncovers the exhaust passage y, leading to the rearward end of the cylinder, and 95 closes the exhaust passage x from the forward end of the cylinder, the motive fluid in the rearward end of the cylinder A will pass through the passage y and exert a pressure 100 on the forward face of the flange c substantially equal to, but preferably less than, and opposed to that exerted by the motive fluid on the end face a, and bottom surface j of the recessed end, so that the pressure in front of the end face b of the valve, due to 105 compression in the cylinder through the port v, will readily throw the valve rearwardly to the opposite position to that indicated in Figure 2, thereby closing the supply of motive fluid to the rearward end of the cylinder, opening the exhaust to the said rearward end of the cylinder, and also opening 110 the supply of motive fluid to the forward end of the cylinder in front of the piston F through the inlet port T and the admission port v. The piston then starts rearwardly 115 and the cycle is repeated.

I claim:

1. In a fluid actuated rock drill of the hammer type, the combination of a cylinder 125 and a reciprocating piston, a valve chest connected to said cylinder, inlet ports and a central exhaust port between said inlet ports at one side of the chest, admission ports in the cylinder corresponding to and 130

- supplied from the said valve chest inlet ports, exhaust ports in the cylinder between the said admission ports and leading to the central portion of the chest, valve bushings 5 in the chest spaced apart at their inner opposed faces to form an exhaust passage through the chest, supply passages in the bushings connecting the valve chest inlet ports and the corresponding cylinder admission ports, a cylindrical valve movable in said bushings and having an enlarged central flange controlling the exhaust passage between the bushings and also having reduced and hollowed or recessed end faces 10 controlling the said supply passages through the bushings, stops within the bushings projecting into the valve against which the bottom portions of the recessed end faces of the valve are adapted to abut for limiting 15 the movement of the valve, and a bolt passing through the bushings, the stops and the valve for holding the parts together, whereby the valve is also guided on the bolt and actuated in one direction or the other by 20 pressure built up through the admission ports of the cylinder and the supply passages of the bushings behind the end faces of the valve, due to compression in the cylinder.
2. In a fluid actuated rock drill of the hammer type, the combination of a cylinder and a reciprocating piston, a valve chest connected to said cylinder, inlet ports and a central exhaust port between said inlet 25 ports at one side of the chest, admission ports in the cylinder corresponding to and supplied from the said valve chest inlet ports, exhaust ports in the cylinder between the said admission ports and leading to the central portion of the chest, valve bushings in the chest spaced apart at their inner opposed faces to form an exhaust passage 30 through the chest, supply passages in the bushings connecting the valve chest inlet ports and the corresponding cylinder admission ports, a cylindrical valve movable in said bushings and having an enlarged central flange controlling the exhaust passage 35 between the bushings and also having reduced and hollowed or recessed end faces controlling the said supply passages through the bushings, stops within the bushings projecting into the valve against which the bottom portions of the recessed end faces of the valve are adapted to abut for limiting 40 the movement of the valve, without permitting the edges of said end faces to abut against adjacent parts of bushings or stops, and thereby effecting control of the motive fluid through the inlet ports at the end faces of the valve, solely by sliding contact 45 between the valve and the bushings, cushioning means for said stops located at the outer ends of the stops, and a bolt passing through the bushings, stops, cushioning means, and the valve for holding the parts together, whereby the valve is also guided on the bolt and actuated in one direction or the other by 50 pressure built up through the admission ports of the cylinder and the supply passages of the bushings behind the end faces of the valve, due to compression in the cylinder.
3. In a fluid actuated rock drill of the hammer type, the combination of a cylinder and a reciprocating piston, a valve chest connected to said cylinder, inlet ports and a central exhaust port between said inlet 55 ports at one side of the chest, admission ports in the cylinder corresponding to and supplied from the said valve chest inlet ports, exhaust ports in the cylinder between the said admission ports and leading to the central portion of the chest, valve bushings in the chest spaced apart at their inner opposed faces to form an exhaust passage 60 through the chest, supply passages in the bushings connecting the valve chest inlet ports and the corresponding cylinder admission ports, a cylindrical valve movable in said bushings and having an enlarged central flange controlling the exhaust pas- 65
- faces of the valve, due to compression in the cylinder.
4. In a fluid actuated rock drill of the hammer type, the combination of a cylinder and a reciprocating piston, a valve chest connected to said cylinder, inlet ports and a central exhaust port between said inlet ports at one side of the chest, admission ports in the cylinder corresponding to and supplied from the said valve chest inlet ports, exhaust ports in the cylinder between the said admission ports and leading to the central portion of the chest, valve bushings in the chest spaced apart at their inner opposed faces to form an exhaust passage 70 through the chest, supply passages in the bushings connecting the valve chest inlet ports and the corresponding cylinder admission ports, a cylindrical valve movable in said bushings and having an enlarged central flange controlling the exhaust pas- 75

sage between the bushings and also having reduced and hollowed or recessed end faces controlling the said supply passages through the bushings, stops within the bushings projecting into the valve against which the bottom portions of the recessed end faces of the valve are adapted to abut for limiting the movement of the valve without permitting the edges of said ends faces to 10 abut against adjacent parts of bushings or stops and thereby effecting control of the motive fluid through the inlet ports at the end faces of the valve, solely by sliding contact between the valve and the bushings, 15 cover plates for the bushings, cushioning

means for said stops located between the stops and the cover plates, and a bolt passing through the cover plates, bushings, cushioning means, stops, and the valve for holding the parts together, whereby the 20 valve is also guided on the bolt and actuated in one direction or the other by pressure built up through the admission ports of the cylinder and the supply passages of the bushings behind the end faces of the valve, 25 due to compression in the cylinder.

In testimony whereof I have signed this specification.

LEWIS C. BAYLES.
